UNITED STATES PATENT OFFICE.

SAMUEL DRESNER, OF CHICAGO, ILLINOIS.

CATCH FOR TRAVELING-BAG FRAMES.

Application filed May 12, 1922. Serial No. 560,286.

To all whom it may concern:

Be it known that I, SAMUEL DRESNER, a citizen of the United States, residing at Chicago, in the county of Cook, State of Illinois, have invented certain new and useful Improvements in a Catch for Traveling-Bag Frames; and I do hereby declare the following to be a full, clear, and exact description of the invention, such as will enable others skilled in the art to which it appertains to make and use the same.

My invention relates to catches or fastenings of the pivoted hook type as employed on traveling bags and the like for preventing a relative movement of the two movable parts in a general direction parallel to the axis on which the latching lever is pivoted, such catches being commonly employed for holding bag frames closed regardless of the locking of the bag. For this purpose, it has long been customary to mount two such catches on the top of the outer frame portion near the upper corners of the bag, each of the said catches having a hinged arm which is adapted to be swung into and out of a position in which it enters a slot in the companion frame portion and having a spring arranged for normally holding the latching arm of the catch in either its locking or unlocking position.

While catches of this kind as now in common use are quite effective when there is no great load within the traveling bag and when no particular strain is exerted on the bag, an undue loading or other straining of the bag, such as that occurring when a well packed bag is roughly handled, is apt to snap these catches open, thereby causing a possible loss or damage to the contents of the bag.

My present invention aims to avoid such occurrences by providing a safety provision which will latch the catch against such accidental releasing, and aims to provide this safety provision in an exceedingly simple and highly effective construction. Furthermore, my invention aims to provide a catch or fastening of this general class which will also interlock the two upper portions of the frame members against relative vertical movement, thereby increasing their effective joint strength and enabling the bag to resist more severe strains.

More particularly, my invention aims to provide a catch of the class described in which the latching arm is slidably mounted

on a pivoted lever and in which this arm has its free end and finger adapted to underhang a part of the inner frame portion when the lever is slid into its safe locking position. It also aims to provide friction means, desirably in the form of a spring, for preventing the latching lever from sliding out of its said locked or safety position and for likewise preventing the lever from sliding when the catch is swung open. Still further and also more detailed objects will appear from the following specification and from the accompanying drawings, in which

Fig. 1 is a perspective view of one upper corner portion of a traveling bag frame equipped with a safety catch embodying my invention and showing this when the catch is closed and latched in its safety position.

Fig. 2 is a view of the same bag parts with the catch unlatched and with the bag frame partly opened to show the perforation through which the tip of the latching lever extends when the catch is closed.

Fig. 3 is a section taken along the correspondingly numbered lines in Fig. 5 through the catch of my invention and the frame portions adjacent thereto, with the catch in its locked or safety position.

Fig. 4 is a similar section taken with the catch in its unlocked position.

Fig. 5 is a section taken transversely of Fig. 3 and along the line 5—5 of that figure.

Fig. 6 is a perspective view of the spring which affords the needed friction for resisting a sliding of the arm of the catch on the lever.

In the embodiment of the drawings, I am showing the catch of my invention as applied to a bag frame which has each of its main portions composed of two strips having their faces at right angles to each other and rigidly connected to each other so as to form the equivalent of two angle steel frames, these frame strips being spaced from each other according to the usual practice to permit of their being covered with leather. The outer frame portion comprises a flat band 1 bent flatwise and designed to extend upwardly along one end of the bag and to extend flatwise horizontally along the top of the bag, this strip 1 being connected by angle braces 2 to a similarly shaped strip 3 which is bent edgewise so as to have its faces vertical.

The companion or inner frame portion consists of similarly arranged parts, namely

a strip 4 extending parallel to the strip 1 and bent flatwise and having its upper face horizontal, this strip 4 being connected by angle braces 5 to another portion 6 of the inner frame which is bent edgewise so as to have its flat faces vertical. Secured to the inner frame portion 6 by a rivet 7 is a latching plate 8 which has its main portion horizontal and which has a substantially rectangular slot or perforation 9 in this main portion. Mounted on the outer frame strip 1 is a latch body 10 which has a perforation 11 alining both with the said perforation 9 in the latching plate 8 and with a perforation 12 in the said outer frame portion 1. This latching body is recessed on its underside so as to raise its top for some distance above the top of the frame member 1 and desirably is secured to that frame portion 20 by fingers 13 extending through perforations in the frame member 1 and clinched against the underside of the same as illustrated in Figs. 3 and 4.

Pivoted to the latch body 10 on a pin 14 which is disposed transversely of the general direction in which the frame member 1 extends horizontally, is a lever 15 which desirably has its free end 16 curved upwardly to facilitate the grasping of the end of the lever when the latter is to be raised, and which lever extends longitudinally of the bag frame. This lever has two portions adjacent to the pin 14 disposed at a decided angle to each other and each adapted to engage the face of a flat spring 17 which is riveted to the underside of the latch body, so that this spring will hold the lever firmly either in its latching position of Fig. 3 or in its unlatching position of Fig. 4.

The latching itself is effected by a latching member carried by the lever and having an arm 18 adapted to project through all three of the said alined perforations when the lever is in its lowered or latching position. Instead of fastening this latching arm rigidly to the lever in accordance with the general practice heretofore employed, I provide the arm with a head 19 resting upon the top of the lever 15 and I permit the arm to extend through a perforation 24 in the lever which corresponds in width to that of the shank of the arm but which is considerably longer (in the direction of the length of the lever) than the corresponding width of the arm portion adjacent to the head 19. Then I provide at least one, and desirably two, pins 20 extending transversely through the arm at some distance below the lever 15 and interpose between these pins and the lever a spring 21 which is so formed that it would normally bow to a greater height than the distance between the said pins and the bottom of the lever. For this purpose, I desirably employ a spring as shown in Fig. 6, 65 which spring has a perforation through

which the shank of the arm extends. Thus arranged, the spring 21 continuously presses the head 19 against the upper face of the lever with such a friction as to resist a sliding of the head on the lever.

To utilize this sliding movement of the arm, I provide the lower or free end of the arm with a projection 22 extending in a general direction away from the pivot of the lever and so disposed as to underhang the latching plate 8 beyond one end of the perforation 9 in the latter when the arm is in its latching position and has been slid away from the axis 14 of the lever as shown in Fig. 3. When the arm is thus slid, the projecting or hook portion 22 of the arm latches the arm against upward movement, so that the arm cannot accidentally be snapped upwards either by strains on the bag or by accidental contact with the lever. Furthermore, the arm when in this position not only cooperates with the side walls of the perforations through which it extends in latching the two frame members against a movement tending to open the bag, but also interlocks the two frame members against vertical separational movement, thereby considerably adding to the strength and rigidity of the bag frame. However, the latch can instantly be unlocked by simply sliding it to the position shown in dotted lines in Fig. 3 and then raising the lever, this sliding being easily effected by digitally moving the head 19 of the arm.

If the arm were slid away from the pivot of the lever while the latter is in its raised position, this might bring the arm to a position in which it would strike against one end of the slot 11 in the latching plate so as to prevent the ready closing movement of the lever. To avoid this, I desirably provide the arm also at its free end with a projection 23 extending towards the pivot of the lever and adapted when the lever is raised to underhang the portion of the latching plate 10 which extends from the perforation 11 towards the pivot of the lever as shown in Fig. 4. This arm 23 will then prevent the arm from being slid along the lever towards the free end of the latter as long as the lever is opened.

With my latch constructed as described, it will be evident that the head 19 of the arm practically acts as a slide mounted on the lever and carrying the arm, and it will also be evident that the highly important advantages secured by my latch are attained by the use of very few added parts and with a simple and inexpensive construction. However, while I have illustrated and described the latch or catch of my invention as applied to a traveling bag in which each frame member has two portions spaced from each other for the greater part of their length to facilitate the attaching of the

leather covering to the same, in which the perforations through which the latching arm operates are in the shape of narrow slots, in which the latching member comprises a head resting on the top of the lever and an arm extending through the lever, and in which a slightly bowed spring affords the friction means for resisting a sliding movement of the latching member with respect to the lever, I do not wish to be limited to these or other details of the construction and arrangement as thus disclosed. Obviously, the various features might be modified in many ways without departing either from the spirit of my invention or from the appended claims.

I claim as my invention:

1. A latch for the usual bail members of a traveling bag or the like, the said bail members comprising upper portions equipped with perforations which aline when the bag is closed, comprising a lever pivotally connected to the outer bail member, a latching member slidably mounted on the lever for movement in a direction transversely of the pivot of the lever, the latching member having an arm projecting through both of the said perforations when the lever is in its closure position, the arm having at its free end a projection adapted to underhang one end of the perforation in the inner frame member when the latching member is slid in one direction while the lever is in its closure position.

2. A latch for the usual bail members of a traveling bag or the like, the said bail members comprising upper portions equipped with perforations which aline when the bag is closed, comprising a lever pivotally connected to the outer bail member, and a latching member slidably mounted on the lever for movement in a direction transversely of the pivot of the lever, the latching member having an arm projecting through both of the said perforations when the lever is in its closure position, the arm having at its free end a projection adapted to underhang one end of the perforation in the inner frame member when the latching member is slid away from the pivot axis of the lever while the lever is in its closure position.

3. A latch for the usual bail members of a traveling bag or the like, the said bail members comprising upper portions equipped with perforations which aline when the bag is closed, comprising a lever pivotally connected to the outer bail member, and a latching member slidably mounted on the lever for movement in a direction transversely of the pivot of the lever, the latching member having an arm projecting through both of the said perforations when the lever is in its closure position, the arm having at its free end a projection adapted to underhang one end of the perforation in the in-

ner frame member when the latching member is slid away from the pivot axis of the lever while the lever is in its closure position, and friction means for resisting a sliding of the latching member.

4. A latch as per claim 3, in which the friction means comprise a bowed spring bearing against a face of the lever, and means on the arm of the latching member tending to flatten the bowed spring and to press it against the lever.

5. A latch as per claim 3, in which the latching member comprises a head bearing against the top of the lever and an arm projecting downwardly through the lever; and in which the friction means comprise a bowed spring bearing against the lower face of the lever, and means on the arm of the slide tending to flatten the bowed spring and continuously pressing it against the lever.

6. A latch for the usual bail members of a traveling bag or the like, the said bail members comprising upper portions equipped with perforations which aline when the bag is closed, comprising a lever pivotally connected to the outer bail member, a latching member slidably mounted on the lever for movement in a direction transversely of the pivot of the lever, the latching member having an arm projecting through both of the said perforations when the lever is in its closure position, the arm having at its free end a projection adapted to underhang one end of the perforation in the inner frame member when the latching member is slid in one direction while the lever is in its closure position, the arm also having at its free end a projection directed oppositely to the aforesaid projection and adapted to engage a portion of the mounting of the lever when the latter is in its unlatching position so as to prevent a movement of the slide while the lever is in that position.

7. A latch as per claim 3, in which the friction means comprise a bowed spring bearing against the lower face of the lever, and means on the arm tending to flatten the bowed spring and to press it against the lever, the lever being recessed on its lower face to house the spring.

8. A bag frame having the usual pair of relatively movable frame members equipped with aligned perforations, a catch comprising a latch body mounted on the outer frame member opposite the said perforations, a lever pivoted on the latch body, and a latching member slidably mounted on the lever and extending through the said perforations when the lever is in its latching position, the latching member having a finger adapted to underhang the inner frame member beyond the perforation in the latter when the latching member is slid in one direction while the lever is in its said position.

9. A bag frame having the usual pair of relatively movable frame members equipped with aligned perforations, a catch comprising a latch body mounted on the outer frame member opposite the said perforations, a lever pivoted on the latch body, and a latching member slidably mounted on the lever and extending through the said perforations when the lever is in its latching position, the latching member having a finger adapted to underhang the inner frame mem-

ber beyond the perforation in the latter when the latching member is slid in one direction while the lever is in its said position, the latching member also having a portion underhanging a part of the latch body when the lever is in its unlatching position to prevent a sliding of the latching member on the lever while the lever is in its unlatching position.

Signed at Chicago, May 5th, 1922.

SAMUEL DRESNER,
